The ornamental design for a receiver-printer interface for a facsimile, as shown and described.

DESCRIPTION

FIG. 1 is a top, front and left side perspective view of a receiver-printer interface for a facsimile showing my new design;

FIG. 2 is a front elevational view thereof;

FIG. 3 is a rear elevational view thereof;

FIG. 4 is a top plan view thereof; and,

FIG. 5 is a left side elevational view thereof, the right side being a mirror image.

The bottom being plane and unornamented.

FIG.1.

FIG.2. **FIG.3.**

FIG.4.

FIG.5.
